UNITED STATES PATENT OFFICE

103,406

DESIGN FOR A WRINGER HEAD OR SIMILAR ARTICLE

Julian L. Perkins, West Springfield, Mass.

Application March 5, 1936, Serial No. 61,493

Term of patent 3½ years

To all whom it may concern:

Be it known that I, Julian L. Perkins, a citizen of the United States, residing at West Springfield, in the county of Hampden and State of Massachusetts, have invented a new, original, and ornamental Design for a Wringer Head or Similar Article, of which the following is a specification, reference being had to the accompanying drawing, forming part thereof.

Fig. 1 is an end elevational view of a wringer head showing my new design; and

Fig. 2 is a side elevational view thereof, and
Fig. 3 is a top plan view thereof.

I claim:

The ornamental design for a wringer head or similar article, as shown.

JULIAN L. PERKINS.
